CONNECTOR WITH TAKE-UP MEANS
Henry G. Colmer, Jr., 4203 Belvedere St., Mobile, Ala.
Filed Sept. 7, 1961, Ser. No. 136,508
5 Claims. (Cl. 254—67)

This invention relates to connectors, and particularly to connectors incorporating take-up devices whereby the connecting element may be drawn taut to hold the connected objects tightly to one another.

It is frequently necessary to fasten securely one object to another by means of a cable, or other flexible member. While this need arises in many fields, a particularly good example is the securing together of a towboat and a barge. Although barges are often pulled behind towboats, in which case it is only necessary to connect the towline to a cleat or butt on the towboat, the towboat and barge are many times lashed side by side. In this latter event, it is essential that the securing means be very tight, so that the two vessels will be held in contact with one another and there will be no bumping or scraping of their sides. Steel cables are frequently used for this purpose, and a connector having some means for taking up the slack and pulling the line taut is required. Hand wheel operated winches, ratchet and chain devices and other conventional winding mechanisms have been used. These have several disadvantages, however, as they are difficult to handle, stand high above the deck and interfere with free movement on the deck, bend the cable as they tighten, and many times are expensive.

The general object of the present invention is to provide a connector which will be easy to operate, inexpensive to manufacture, and will occupy little space on a boat deck.

A more specific object of the invention is to provide a connector which has a take-up mechanism capable of operation at two speeds, to rapidly take-up slack, and more slowly and with more power, pull the line tight.

Another object of the invention is the provision of a connector of this type wherein the pull exerted upon a cable will be in a straight line and the cable will not be weakened by bending.

A further object is the provision of a connector which will permit its operating members to collapse when not in use so that there will be no upstanding parts to interfere with free movement around the deck.

Still another object of the invention is to provide a connector which has an auxiliary operating member to permit the application of additional power when required.

Yet a further object is the provision of apparatus of this character which can be operated much more safely than those previously used.

Other objects of the invention will become apparent from the following description of one practical embodiment thereof, when taken in conjunction with the drawings which accompany, and form part of, this specification.

In the drawings:

FIGURE 1 is a side elevational view of a connector embodying the principles of the present invention;

FIGURE 2 is a top plan view of the connector;

FIGURE 3 is an enlarged vertical, transverse section, taken on the line 3—3 of FIGURE 1, illustrating the cable hook and screw forward guide;

FIGURE 4 is another vertical, transverse section, taken on the line 4—4 of FIGURE 1, showing the auxiliary ratchet operator and the operating handle frame;

FIGURE 5 is a horizontal section through the screw-advancing nut, and is taken on the line 5—5 of FIGURE 1; and

FIGURE 6 is a perspective view of the nut-supporting hub.

2

In general, the invention consists of a base frame, fixed to a boat deck, or other surface, and supporting a screw-advancing nut to move a screw longitudinally to tighten a cable connected to the end of the screw. There are means for advancing the nut bodily along the base for rapid take up of slack, and for rotating the screw to obtain a power tightening of the line. A ratchet and lever are provided for rotating the nut when greater leverage is required. The operating handle for the take-up mechanism is partially collapsible when not in use.

Referring to the drawings in detail, the base 1 of the connector consists of a pair of transversely spaced, parallel side plates 2, which are bridged at their ends by a front plate 3 and a back plate 4. Intermediate spacers 5 connect the plates at their bottoms. While the base could be fastened to a boat deck by bolts through spacers 5, it is preferred to weld the base to the boat deck. The front plate is notched at its top center, as at 6, to slidably receive the connector screw, hook, or the cable, depending upon the longitudinal position of the take-up mechanism relative to the base. A bail 7 bridges the top of the front plate to prevent upward movement of the connector elements. The back plate 4 is recessed in its top, as at 8, to seat the operating handle when collapsed, as will be described.

The upper edges of the rear portions of the side plates are indented to provide a plurality of rearwardly inclined notches 9. The notches of the two side plates are aligned transversely to provide a series of seats at progressively greater distances from the front end of the base. These provide means for a fast preliminary takeup of the cable, as will be explained.

The forward portions of the side plates have guide rails 10 mounted upon their tops to support a hook carriage 11. The carriage has a pair of rail slides 12, which encircle the exposed portions of the rails 10 and hold the carriage on the rails for sliding movement. A slotted pelican hook shank 13 projects forwardly from the carriage, and a beak hinging loop 14 and locking loop 15 are mounted in the slot 16 of the shank. The beak 17 of the hook is pivotally connected to the hinge loop, and has its bill end 18 resting upon the shank 13. Locking loop 15 is slipped over the bill end of the beak and holds it against the shank. Wings 19 project forwardly from the shank to underlie the hinge loop 14 to prevent it from dropping down as the cable is being handled to take up the slack. The carriage has a pair of spaced arms 20 at the rear, between which one end of a take-up screw 21 is pivotally mounted by means of a pin 22.

The opposite end of screw 21 is threaded through a nut 23 which is supported on the base by means of a bridge 24. The bridge includes a hub 25 which surrounds and rotatably journals the nut 23. The hub carries outwardly projecting studs 26 which are adapted to seat in selected notches 9 to mount the bridge on the base.

A U-shaped stirrup is provided which is pivotally mounted on the studs 26. The stirrup includes a pair of legs 27, through which the studs pass, and a cross-member 28. The legs have upwardly extending ears 29, and the cross-member is connected to the ears by means of a pivot pin 30 which passes through the ears and through a sleeve-supporting arm 31 which is fixed to the center of the cross-member. U-shaped stop members 32 are mounted at the tops of the legs to limit the rotative movement of the cross-member relative to the legs. The lower member 33 of the stop limits the downward movement of the cross-member to a position at right angles to the legs, while the upper member 34 will prevent the cross-member from swinging too far to the rear. The supporting arm carries a sleeve 35 which is parallel to the legs 27 when the cross-member is seated at the tops

of the legs. Of course, when the cross-member pivots, the sleeve swings with it.

The nut 23 carries a bevel gear 36 by means of which it may be rotated. This gear is in mesh with another bevel gear 37, at right angles to the gear 36 and held by a bracket 38 bolted to flange 39 of hub 25. Gear 37 has a squared end 40 that is engaged by a coupling sleeve 41, carried at the bottom of an operating shaft 42 slidably and rotatably mounted in the sleeve 35. An operating handle 43 is fixed to the top of shaft 42. It will be clear that with shaft 42 coupled to the squared end 40 of gear 37, rotation of the shaft will cause rotation of nut 23 and axial movement of screw 21 relative to the base.

The legs 27 of the stirrup terminate in feet 44 which extend horizontally forward when the stirrup and shaft 42 are in vertical, operative position. The feet end in toes 45 for contact with the deck in preliminary setting up of the bridge and taking up slack in the cable, as will be described.

In order to allow for the use of greater power in rotating nut 23 than would be possible by rotating the operating handle, the nut has a ratchet 46 on its end opposite the gear 36. A lever 47 is pivoted on the hub and carries a pawl 48 for engagement with the teeth of the ratchet. The pawl is held against the ratchet by means of a spring 49, fixed to the lever and to a pin 50 carried by the pawl. The pin projects through a slot 51 in the lever to permit it to be moved to lift the pawl from the ratchet when the screw is to be turned back to release the cable.

As mentioned above, the base will be welded to the deck of a vessel, or to any other platform where it is to be used. In connecting a towline, the cable 52 has its loop 53 slipped over the bill 18 of the hook beak 17 and the beak is rotated to rest upon the hook shank 13. Lock ring 15 is slipped over the bill to hold the hook closed. The bridge assembly can then be moved back along the base to take the slack out of the cable and position the studs 26 in the proper notches 9. If the cable is hard to pull taut, the bridge assembly can be tilted forward to rest upon the toes 45 and the assembly rocked back by pulling on the handle 43. This will cause the unit to fulcrum about the toes 45 and swing the studs into a more rearwardly positioned notch with the cable taut. After positioning the bridge, the operating handle can be rotated to revolve the nut and cause the screw to move rearwardly. This will tighten the cable. If additional power is needed, the ratchet lever can be rocked to cause further take-up of the screw. The leverage of the ratchet lever can be increased by slipping a length of pipe over the end of the lever.

When the cable is as tight as desired, handle 43 can be lifted to disconnect shaft 42 from gear 37, and the shaft, sleeve, and stirrup rocked about the studs 26 to cause the operating mechanism to assume a horizontal position. The sleeve and its connected cross-member 27 can rock around the pivot 30 to bring the handle and shaft to a truly horizontal position so that the entire coupling will present little height and, therefore, little obstruction to free movement about the deck.

In order to release the cable, the operating handle will be reset in upright position, the pawl lifted from the ratchet, and the handle 43 rotated in reverse direction to retract the screw and loosen the cable. As soon as the cable is loosened, the entire handle and bridge assembly can be lifted from the base by tilting forward the bridge assembly to rest upon the toes 45 and the assembly rocked back by pulling on handle 43. This will cause the unit to fulcrum about the toes 45 and swing the studs 26 clear of the top of the rear portions of the side plates. The bridge assembly can then be moved forward along the base to re-position the studs 26 in the proper notches

9. This will allow the cable to slacken. The cable can then be released from the hook.

While in the above one practical embodiment of the invention has been disclosed, it will be understood that the details of structure shown and described are merely by way of example and the invention may take other forms within the scope of the appended claims.

What is claimed is:

1. A connector comprising, a base having a pair of spaced parallel side bars, the side bars each having an opposed plurality of longitudinally spaced notches forming a plurality of seats, a bridge member having means for seating in selected opposed notches of the pluralities of notches in the side bars, a nut rotatably carried by the bridge member, a screw threaded through the nut for axial movement longitudinally of the base when the nut is rotated, a hook carried at one end of the screw, means carried by the bridge member and coupled to the nut for manual rotation of the screw, and a carriage mounted on the side bars for sliding movement therealong, said carriage supporting the hook and the end of the screw carrying the hook.

2. A connector comprising, a base having a pair of spaced parallel side bars, the side bars each having an opposed plurality of longitudinally spaced notches forming a plurality of seats, a bridge member having means for seating in selected opposed notches of the pluralities of notches in the side bars, a nut rotatably carried by the bridge member, a screw threaded through the nut for axial movement longitudinally of the base when the nut is rotated, a hook carried at one end of the screw, means carried by the bridge member and coupled to the nut for manual rotation of the screw, the means coupled to the nut including a bevel gear fixed to the nut, a second bevel gear in mesh with the first mentioned gear rotatably mounted on the bridge member, an operating shaft rotatably carried by the bridge member and releasably coupled to the second bevel gear, a ratchet fixed to the nut, a lever rockably mounted on the nut, and a pawl carried by the lever for engagement with the ratchet to rotate the nut when the lever is rocked in one direction.

3. A connector as claimed in claim 2 wherein, a stirrup is pivotally mounted on the bridge member for rocking movement in the vertical longitudinal plane of the base, a sleeve mounted in operative engagement with the stirrup, the shaft being rotatably and slidably mounted in the sleeve, and a fulcrum carried by the stirrup for engagement with the surface upon which the base is mounted to permit bodily movement of the bridge member relative to the base when the stirrup is rocked about the fulcrum.

4. A connector as claimed in claim 3 wherein, the sleeve is pivotally connected to the stirrup to permit limited rocking movement of the sleeve relative to the stirrup.

5. A connector as claimed in claim 4 wherein there is a carriage mounted on the side bars for sliding movement therealong, said carriage supporting the hook and the end of the screw to which the hook is connected.
